(57) **CLAIM**

The ornamental design for a set of decorative numbers, as shown and described.

DESCRIPTION

FIG. 1 is a front, right and top perspective view of the number **0** of a set of decorative numbers showing my new design;

FIG. 2 is a rear, left and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, right and top perspective view of the number **1** of a set of decorative numbers showing my new design;

FIG. 10 is a rear, left and bottom perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a front, right and top perspective view of the number **2** of a set of decorative numbers showing my new design;

FIG. 18 is a rear, left and bottom perspective view thereof;

FIG. 19 is a front elevation view thereof;

FIG. 20 is a rear elevation view thereof;

FIG. 21 is a left side elevation view thereof;

FIG. 22 is a right side elevation view thereof;

FIG. 23 is a top plan view thereof;

FIG. 24 is a bottom plan view thereof;

FIG. 25 is a front, right and top perspective view of the number **3** of a set of decorative numbers showing my new design;

FIG. 26 is a rear, left and bottom perspective view thereof;

(Continued)

FIG. 27 is a front elevation view thereof;
 FIG. 28 is a rear elevation view thereof;
 FIG. 29 is a left side elevation view thereof;
 FIG. 30 is a right side elevation view thereof;
 FIG. 31 is a top plan view thereof;
 FIG. 32 is a bottom plan view thereof;
 FIG. 33 is a front, right and top perspective view of the number 4 of a set of decorative numbers showing my new design;
 FIG. 34 is a rear, left and bottom perspective view thereof;
 FIG. 35 is a front elevation view thereof;
 FIG. 36 is a rear elevation view thereof;
 FIG. 37 is a left side elevation view thereof;
 FIG. 38 is a right side elevation view thereof;
 FIG. 39 is a top plan view thereof;
 FIG. 40 is a bottom plan view thereof;
 FIG. 41 is a front, right and top perspective view of the number 5 of a set of decorative numbers showing my new design;
 FIG. 42 is a rear, left and bottom perspective view thereof;
 FIG. 43 is a front elevation view thereof;
 FIG. 44 is a rear elevation view thereof;
 FIG. 45 is a right side elevation view thereof;
 FIG. 46 is a left side elevation view thereof;
 FIG. 47 is a top plan view thereof;
 FIG. 48 is a bottom plan view thereof;
 FIG. 49 is a front, right and top perspective view of the number 6 of a set of decorative numbers showing my new design;
 FIG. 50 is a rear, left and bottom perspective view thereof;
 FIG. 51 is a front elevation view thereof;
 FIG. 52 is a rear elevation view thereof;
 FIG. 53 is a left side elevation view thereof;
 FIG. 54 is a right side elevation view thereof;
 FIG. 55 is a top plan view thereof;
 FIG. 56 is a bottom plan view thereof;
 FIG. 57 is a front, right and top perspective view of the number 7 of a set of decorative numbers showing my new design;
 FIG. 58 is a rear, left and bottom perspective view thereof;
 FIG. 59 is a front elevation view thereof;
 FIG. 60 is a rear elevation view thereof;
 FIG. 61 is a left side elevation view thereof;
 FIG. 62 is a right side elevation view thereof;
 FIG. 63 is a top plan view thereof;
 FIG. 64 is a bottom plan view thereof;
 FIG. 65 is a front, right and top perspective view of the number 8 of a set of decorative numbers showing my new design;
 FIG. 66 is a rear, left and bottom perspective view thereof;
 FIG. 67 is a front elevation view thereof;
 FIG. 68 is a rear elevation view thereof;
 FIG. 69 is a left side elevation view thereof;
 FIG. 70 is a right side elevation view thereof;
 FIG. 71 is a top plan view thereof;
 FIG. 72 is a bottom plan view thereof;

FIG. 73 is a front, right and top perspective view of the number 9 of a set of decorative numbers showing my new design;
 FIG. 74 is a rear, left and bottom perspective view thereof;
 FIG. 75 is a front elevation view thereof;
 FIG. 76 is a rear elevation view thereof;
 FIG. 77 is a left side elevation view thereof;
 FIG. 78 is a right side elevation view thereof;
 FIG. 79 is a top plan view thereof; and,
 FIG. 80 is a bottom plan view thereof.

The broken lines in the figures depict portions of the set of decorative numbers that form no part of the claimed design.
